(57) **CLAIM**

The ornamental design for a semi-automated pipetting apparatus as shown and described.

DESCRIPTION

2. Semi-automated pipetting apparatus

2.1 : Back

2.2 : Bottom

2.3 : Front

2.4 : Left

2.5 : Perspective

2.6 : Right

2.7 : Top

1. Name of the product of this design: semi-automated pipette apparatus; 2. Use of the designed product: the designed product is used for precise pipetting of liquids in the process of experiment; 3. The main design point of this design product: it is in the shape; 4. The picture or photo-
